CLAIM

The ornamental design for a basket, as shown and described.

DESCRIPTION

FIG. 1 is a top, right, front perspective view of a basket showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a bottom plan view thereof; and,

FIG. 7 is a top plan view thereof.

The broken line showing represents unclaimed portions of the article and forms no part of the claimed design.
